UNITED STATES PATENT OFFICE.

HENRY KESSLER, OF SAN FRANCISCO, CALIFORNIA.

REGULATOR FOR STEAM-PUMPS.

SPECIFICATION forming part of Letters Patent No. 250,076, dated November 29, 1881.
Application filed May 9, 1881. (No model.)

To all whom it may concern:

Be it known that I, HENRY KESSLER, of San Francisco, in the county of San Francisco and State of California, have invented a new 5 and useful Automatic Boiler-Regulator for Steam-Pumps, of which the following is a specification.

The object of my invention is to provide a feed boiler-regulator for steam-pumps, so as 10 to keep the water at all times to the desired height in the boiler and regulate the speed of the pump in an automatic manner. I attain this object by the mechanism illustrated in the accompanying drawing, which is a vertical section, partly in elevation.

The metal casing A stands vertically, and is connected to the steam-boiler by means of the pipes K and L—the pipe L entering the boiler below the water-line, and the pipe K entering 20 the boiler above the water-line, as shown—in which position the casing is held so as to bring the horizontal line B B to a level with the water-line of the boiler. The casing is also divided horizontally at the line B B, and a chamber, I, is 25 formed therein, the two parts being connected and held together by bolts *a a*. In this chamber I place an air-tight float or globe, C, of sufficient capacity, when partly immersed in water, of sustaining the stem or rod D and 30 valve E, the rod being connected to the valve by a nut, *b*. The balance-valve E is provided with V-shaped ports F, which are cut through it from the inside to the outside thereof. Leading into this valve is the steam-passage G, 35 which connects with the steam-cylinder of the pump, and above the valve E is the pipe or passage H, which connects with the steam-boiler at any point above the water-line.

Attached to the lower end of the casing is 40 an exhaust or drain cock, M.

The object of the steam-passage which leads from the steam-chamber of the boiler and enters the chamber I through the medium of the pipe K, as shown, and the passage which leads 45 from the boiler from below the water-line and enters the chamber I through the medium of the pipe L, is to keep the float C balanced, it being intended that the steam which is admitted from the boiler through the pipe K and 50 the water from the boiler through the pipe L

shall be equal in pressure, and thus keep the float in position at all times, except when the cock M is opened.

The action is as follows, to wit: When the water is below the line B B in the chamber I 55 the float C and balance-valve E will descend, and steam from the boiler is admitted into the pipe H and valve E, and passes through the ports F into the pipe G, which leads to the steam-cylinder of the pump, which accelerates 60 the speed of the pump, and when the water rises in the steam-boiler the float C, with balance-valve H, will descend and close the ports F of the valve, and thus diminish the steam-supply to the pump, which, in turn, diminishes 65 the supply of water to the steam-boiler, and so on in a regular, automatic manner. The pressure, being equal on the steam-pipe K and water-pipe L, will keep the float in position.

Should it be found desirable to provide the 70 boiler with a greater supply of water than that intended as the regular height or water-line, this may be accomplished by shutting off the water-supply to the chamber I by means of a cock, *c*, connected to the supply-pipe L, and 75 opening the drain-cock M, which draws the water from the chamber I and causes the valve E to descend, carrying the float C to its seat at the base of the chamber, which admits a full head of steam through the passage G to 80 the pump.

Having thus described my invention, what I claim, and desire to secure by Letters Patent, is—

In an automatic boiler-regulator for steam-pumps, having a casing, A, and chamber I, the combination of the float C, provided with stem D, and valve E, with the ports F, communicating with the steam and water passages G, H, K, and L, and drain-cock M, all constructed, arranged, and operating substantially as and for the purpose specified.

In testimony that I claim the foregoing I have hereunto set my hand and seal this 21st day of April, 1881.

HENRY KESSLER. [L. S.]
